Patented Jan. 3, 1899.

A. L. STEWART.
SHIELD OR PROTECTOR FOR LADIES' SHIRT WAISTS.

(Application filed Dec. 6, 1898.)

UNITED STATES PATENT OFFICE.

AMELIA L. STEWART, OF MARTINSBURG, WEST VIRGINIA.

DESIGN FOR A SHIELD OR PROTECTOR FOR LADIES' SHIRT-WAISTS.

SPECIFICATION forming part of Design No. 29,952, dated January 3, 1899.

Application filed December 6, 1898; Serial No. 698,476. Term of patent 7 years.

To all whom it may concern:

Be it known that I, AMELIA L. STEWART, a citizen of the United States, residing at Martinsburg, in the county of Berkeley and State 5 of West Virginia, have invented and produced a new and original Design for a Back Shield or Protector for Ladies' Shirt-Waists, of which the following is a specification.

My invention relates to a new and improved 10 design for a back shield or protector for ladies' shirt-waists, and is illustrated in the accompanying drawing, in which the figure is a perspective view.

The leading feature of my design consists 15 in a back shield or protector for ladies' shirt-waists consisting of a thin body widened intermediate its top and bottom edges, having its sides converging from said widened portion downwardly to its bottom on slightly- 20 curved lines, the extremities of the converging sides being joined by a substantially straight bottom having laterally-extending tapes. The sides of the protector extend upwardly from said widened portion in curved 25 lines, the upper portion of the body being cut away, except at its sides, to form top side projections, from which extend tapes.

In the said drawing the reference-numeral

1 indicates the body of the shield or protector, having the widened part 2 intermediate 30 its top and bottom. From this widened part the sides of the body converge downwardly in slightly-curved lines 3 to the bottom, which is substantially straight, as at 4, and has laterally-extending tapes 5 6. The sides of the 35 body extend upwardly from the widened portion 2 in curved lines 7, and the top portion of said body is cut away, as at 8, to provide top side projections 9, as shown, from which tapes 10 11 extend. 40

My design presents a shirt-waist shield or protector of new and distinguished appearance.

Having thus described my invention, what 45 I claim is—

The design for a shield or protector for ladies' shirt-waists, substantially as herein shown and described.

In testimony whereof I have hereunto set my hand in presence of two subscribing witnesses. 50

AMELIA L. STEWART.

Witnesses:

H. H. EMMERT,
WM. T. STEWART.
